UNITED STATES PATENT OFFICE.

ERNEST A. DE WOLF, OF CRANSTON, RHODE ISLAND, ASSIGNOR TO UNIVERSAL WINDING COMPANY, OF BOSTON, MASSACHUSETTS, A CORPORATION OF MASSACHUSETTS.

COP HOLDER FOR WINDING MACHINES.

Application filed May 25, 1927. Serial No. 194,169.

This invention relates to improvements in cop-holders for winding machines for winding cops, cones or packages of yarn, thread and other textile material.

- 5 The invention relates particularly to means for rotatably mounting a core or holder to adapt it to be driven from a friction drive-roll or drum to wind the strand material thereon.
- 10 One object of the improvement is to provide friction-reducing bearings for the cop-holder to adapt it to rotate at high speed with a minimum of resistance to the drive.

Another object of the improvement is to 15 provide bearings of the oilless type for the cop-holder to avoid the use of lubricant liable to drip or to be thrown on to the material being wound.

Another object of the improvement is to 20 provide bearing means for the cop-holder which are simple in construction, economical to manufacture and of maximum durability over long periods of use.

Further objects of the improvement are 25 set forth in the following specification which describes a preferred form of construction of the invention as illustrated in the accompanying drawings. In the drawings:

Fig. 1 is a part sectional view showing my 30 improved cop-holder as embodied in a wooden or fiber cone or core mounted to rotate on a dead-spindle and carrying a conical cop or package driven from a cylindrical drum or drive-roll; and

35 Fig. 2 is a similar view of the cone-holder and its mounting showing the bearings therefor in section.

In the present specification I have preferred to describe my improved cop-holder 40 as adapted for winding conical cops on a wooden or fiber core or support, but it is to be understood that the core may take other forms and be constructed of any suitable material.

45 In friction or drum-driven winding machines the cop or package is usually wound on a core or holder which is rotatably mounted on a dead-spindle and adapted to be driven through surface contact of the winding with a rotating drum or drive-roll. As 50 herein shown the dead-spindle 2 is swiveled at the end of an arm 3 and is normally held in inclined relation with respect to the periphery of the drive-roll 4. The arm 3 may be suitably arranged to adapt the cop-holder

to move away from the drive-roll as the package increases in size during the winding. The cop may be wound of either cylindrical or conical form and various types of cores or holders are employed for supporting the package at its center. In some cases paper or cardboard tubes are used for this purpose and in other instances wooden, composition or fiber cores or mandrels are employed.

As herein illustrated the cop-holder 5 consists of a substantially solid, conical core or mandrel which may be constructed of hard wood, composition, fiber or any other suitable material. The core or holder 5 is 70 provided with an axial bore 6 extending substantially throughout its length and terminating at the apex end in a bore 7 of less diameter. The larger bore 6 is adapted to receive the bearings 10 for rotatably supporting the core or holder 5 on the dead-spindle 2.

In accordance with the present improvement the bearings 10 are constructed in the form of cylindrical sleeves or bushings 80 made from wood or fiber impregnated with graphite or other similar lubricant. This type of bearing is well known in various arts as an oilless bearing and possesses maximum wearing qualities without requiring lubrication.

It will be noted from Fig. 2 of the drawings that the dead-spindle 2 is formed at one end with an enlarged shank or butt 11 providing an abutment or square shoulder 90 12 against which one of the bushings 10 bears. The two bushings 10 are spaced apart by a cylindrical sleeve 15 extending between their ends and enclosing the spindle 2 with a free fit. The sleeve 15 is of less 95 outside diameter than the bearing-sleeves or bushings 10 so as to clear the interior of the bore 6 of the cop-holder or core 5. The outer sleeve or bushing 10 is held in place by a flat washer 16 maintained in position 100 on the spindle 2 by means of a split wire ring 17 sprung into a peripheral groove 18 cut in the surface of the spindle.

The cop-holder or core 5 has its larger bore 6 of suitable diameter to adapt it to 105 slide over the two bearings 10 and the outer end of the spindle 2 projects through its smaller bore 7 with a slight clearance there-around. The core or holder 5 may be held in place on its bearings by any suitable 110

means and I have herein illustrated a conventional form of detent-latch 20 for this purpose. Referring particularly to Fig. 2 of the drawings, the latch 20 is pivotally mounted in a slot at the end of the spindle 2 by means of a cross-pin 21 extending through the sides thereof. A plunger-pin 23 slides in an axial bore 24 in the end of the spindle 2 and is pressed outwardly by 5 means of a helical spring 25. When the latch 20 is swung into open position as illustrated in Fig. 2 to permit the core or holder 5 to be slid into place on its bearings 10 the plunger 23 impinges against the flat inner 10 end of the latch 20 to hold it in this position. To secure the core or holder 5 in place on the spindle 2 the latch 20 is rocked into the position shown in Fig. 1, the plunger 23 being thereby retracted to slide 15 across the end of the latch and engage with its side to hold it in this position.

It will be observed that the present invention provides an extremely simple and efficient means for rotatably mounting a cop- 20 holder on a dead-spindle. The device comprises only three main elements in addition to the spindle itself, namely, the two bearing-bushings of oilless type and the separating sleeve. These elements are economical to manufacture or to purchase as merchantable articles and their assembling or 25 mounting on the spindle requires very little machine work.

The complete device provides a mounting 30 which requires no lubrication so that the danger of oil dripping or being thrown and spattered on the yarn, thread or other textile material constituting the cop or package is eliminated. It will be understood 35 that cop-holders of the present type must rotate at high speed and the present form of bearing-support is practically proof against friction and wear or deterioration from such high speed operation. It is to 40 be further noted that while I have illustrated the improved device as serving as a support or mounting for a particular type 45 of cop-holder, it is also adapted for other

forms of cores or cop-tubes. It is also to be understood that while I have herein illustrated a preferred form of construction of the device, various modifications may be made in the structure and arrangement of its parts without departing from the spirit or scope of the invention. Therefore, without limiting myself in this respect, 50 55

I claim:

1. In a mounting for cop-holders the combination of a spindle, a bushing composed of friction-reducing material rotatable on the 60 spindle, and means for retaining the bushing in place on the spindle to adapt it to be received within the bore of the cop-holder to rotatably support the latter.

2. A device of the type specified comprising a spindle, bushings constructed of lubricant-impregnated material rotatably mounted on the spindle, a cop-holder having a bore adapting it to slide over the bushings to be rotatably supported thereby, and 70 means for retaining the cop-holder in place longitudinally of the spindle.

3. A device of the type specified comprising a spindle, a pair of bushings constructed of lubricant-impregnated material rotatably 75 mounted on the spindle, a sleeve surrounding the spindle and extending between the bushings to hold them in spaced relation, and means for holding the bushings in position longitudinally of the spindle.

4. A device of the type specified comprising a dead-spindle projecting from a shank forming a shoulder at one end, a plurality of bushings of lubricant-impregnated material rotatably mounted on the spindle with 85 one of them abutting the shoulder at its end, a sleeve enclosing the spindle and extending between the bushings to maintain them in spaced relation, a washer abutting the end of the outer bushing, and means for securing the washer on the spindle to retain the bushings in place longitudinally thereof.

In testimony whereof I hereunto affix my signature.

ERNEST A. DE WOLF.
